TWO-SPEED DRIVING TOOL

Harry A. Pitzer, Jr., Cumberland, Md.

Application January 13, 1950, Serial No. 138,393

1 Claim. (Cl. 74—130)

1

This invention relates to a novel construction of driving tool for use with screwdriver bits, drill bits or other bits which are actuated by being rotated on their longitudinal axis, and has for its primary object to provide a novel construction of tool whereby a bit will be revolved on its longitudinal axis by a force exerted on the tool in a direction axially thereof and of the tool bit.

More particularly, it is an aim of the present invention to provide a tool which may be readily adjusted for varying the speed at which the tool bit will be revolved relatively to the speed of sliding movement of the actuating means relatively to the tool bit for adapting the tool to work requiring different degrees of force, as for example in applying a screw to a hardwood surface and to a softer, more penetrable wood.

Still a further object of the invention is to provide a tool having means for automatically returning it to an extended position preparatory to receiving another power stroke to enable the tool to be rapidly operated by a reciprocating movement wherein force is exerted by the operator in only one direction.

Still another object of the invention is to provide a tool having means for releasably locking the tool bit relatively to the reciprocating tool parts whereby all parts of the tool revolve in unison, thereby readily adapting the tool for use in removing a screw.

Various other objects and advantages of the invention will hereinafter become more fully apparent from the following description of the drawings, illustrating presently preferred embodiments thereof, and wherein:

Figure 1 is a side elevational view, partly in vertical section and showing the tool in a projected position;

Figure 2 is a view similar to Figure 1 but showing the tool in a retracted position and looking from left to right of Figure 1;

Figures 3 and 4 are cross sectional views of the tool taken substantially along planes as indicated by the lines 3—3 and 4—4, respectively, of Figure 2;

Figure 5 is a plan view looking toward the inner side of a part of the tool;

Figure 6 is a cross sectional view thereof taken substantially along a plane as indicated by the line 6—6 of Figure 5;

Figure 7 is a side elevational view of another section of the tool, likewise shown removed;

Figure 8 is a cross sectional view thereof taken substantially along a plane as indicated by the line 8—8 of Figure 7;

2

Figure 9 is a side elevational view of the shift lever shown removed;

Figure 10 is a fragmentary vertical sectional view, partly in side elevation of a modification 5 of the tool of Figures 1 to 9, and

Figure 11 is a cross sectional view of a modified form of tool taken substantially along a plane as indicated by the line 11—11 of Figure 10.

Referring more specifically to the drawings, and first with reference to the embodiment as illustrated in Figures 1 to 9, the two speed driving tool in its entirety and which comprises the invention is designated generally 12 and includes a tubular housing or barrel 13 in one open end 15 of which is received a cap 14 and the other open end of which receives the enlarged end of a longitudinally tapered bearing 15 which extends outwardly from the last mentioned end of the housing 13. The cap 14 and bearing 15 are detachably secured in the ends of the housing 13 each by a plurality of screw fastenings 16. The cap 14 is provided with two inwardly opening recesses 17 and 18 and the bearing 15 has two inwardly opening recesses 19 and 20 which are in longitudinal alignment with the recesses 17 and 18, respectively. A rod 21 extends longitudinally through the housing 13 and has its ends seated in the recesses 17 and 19 and a shift rod 22 likewise extends longitudinally through the housing 13 and has its ends engaging in the recesses 18 and 20 and is mounted for swivel movement therein. The ends of the rod 22 are normally spaced from the beds of the recesses 18 and 20 to permit a slight sliding movement of the rod 22 longitudinally of the housing 13, for a purpose which will hereinafter become apparent.

An elongated core or frame, designated generally 23, best illustrated in Figure 5 and which is substantially half circular in cross section, is detachably supported within the housing 13 and secured thereto by a screw fastening 24. The core or frame 23 extends substantially from end-to-end of the housing 13 and affords a slight space between one end thereof and the cap 14 and a somewhat larger space between its opposite end and the bearing 15, as clearly illustrated in Figures 1 and 2. The core 23 is provided with diametrically opposed inwardly facing channels 25 and 26 forming rails or runways, for a purpose 45 which will hereinafter become apparent. Adjacent the runway 25, the core 23 is internally thickened and toothed to provide spaced rack portions 27 and 28 which are spaced different distances from the plane of the tracks 25 and 55 26, and said internally thickened portion is re-

cessed between the racks 27 and 28 to provide a channel or free way 29.

A carriage, designated generally 30 and best illustrated in Figures 7 and 8 includes a frame or body portion 31 having a relatively large opening 32 in one end thereof and a longitudinally extending bore 33, one end of which opens into the opening 32 and the other end of which opens outwardly of the lower end 34 of said body member 31. A driving tool bit 35, and herein illustrated as a screwdriver bit, has an elongated shank 36 which extends reciprocally and rotatably through a longitudinal bore 37 of the bearing 15 and which bore is disposed axially of the housing 13. The bore 37 preferably contains a bushing 38 in which the tool bit shank 36 is rotatably and slidably disposed. Said tool bit shank 36 is relatively long and extends inwardly from the bearing 15 through the bore 33 and into the opening 32. A hub 39 having a socket opening outwardly of its lower end is mounted on the end of the shank 36 which is disposed in the opening 32 and for rotation relatively thereto. Said hub 39 is provided at its upper end with a beveled gear 40 and at its lower end with a clutch half 41. The clutch half 41 is provided with a depending annular toothed portion all of the teeth of which are inclined in the same direction for engagement with a similar upwardly facing toothed portion of a lower clutch half 42 which is likewise disposed within the opening 32 and slidably keyed to the bit shank 36 by a key 43 thereof which engages a longitudinally extending groove 44 of said bit shank. A spring 45 is mounted on the shank 36 between the lower end of the lower clutch half 42 and the surface of the body 31 defining the lower end of the opening 32 for yieldably retaining the teeth of the clutch halves 41 and 42 in intermeshing engagement, as best illustrated in Figure 7. Between the opening 32 and the lower end 34, the body member 31 is provided with an opening 46 through which a portion of the shank 36 extends and which contains an anti-friction thrust bearing 47 which is mounted on the shank 36 and supported by a thrust collar 48 which is adjustably secured to the shank 36 and which is likewise disposed in the opening 46. The thrust bearing 47 bears against the top wall of the opening 46 to provide an anti-friction support for the carriage 30 on the bit shank 36.

The carriage 30 near its lower end is provided with transversely aligned outwardly projecting stub axles 49 on each of which is journaled a roller 50. The carriage body 31 is provided near its opposite, upper end with transversely aligned bearing openings 51 for journaling a shaft 52 which extends transversely through the opening 32 above the beveled gear 40. A roller 53 is mounted on each end of the shaft 52. The complementary rollers 50 and 53 are disposed in longitudinal alignment and are spaced outwardly from the side edges of the carriage body 31 and are adapted to engage the track ways 25 and 26, as best illustrated in Figure 3 for mounting the carriage 30 for reciprocating movement within the housing 13 and longitudinally thereof and of the core 23. As seen in Figure 3, the carriage 31 is provided with a laterally projecting ear 54 having an opening therethrough extending longitudinally of the housing 13 and through which the rod 21 slidably extends. An expansion coil spring 55 is mounted on the rod 21 between the cap 14 and said ear 54 for yieldably urging the carriage 30 and the parts connected thereto

downwardly with respect to the housing 13 and core 23 from the projected position of the parts, as illustrated in Figure 1 to their retracted positions of Figure 2, so that the carriage 30 will normally be disposed in its position of Figure 2.

5 A compound gear 56 is disposed in the opening 32 and slidably splined as seen at 57 in Figure 8 to the shaft 52. Said gear 56 includes a large gear portion 59 forming a ratchet wheel for engagement with the rack 27 and a smaller gear portion 60 for engagement with the rack 28 and which is spaced from the gear 59. A disk 61 is 10 suitably secured to the enlarged end or side of the compound gear 56 and has a laterally offset peripheral portion or flange 62 which is spaced 15 from the gear 59. A beveled gear 63 is fixed to the shaft 52 independently of the gear 56 and is disposed in meshing engagement with the beveled gear 40. A portion of the shift rod 22 is provided 20 with a laterally extending web 64, the outer longitudinal edge of which engages between a portion of the gear 59 and the flange 62 so that by turning the shift rod 22 the compound gear 56 may be displaced longitudinally of the 25 shaft 52 for positioning either the gear 59 in engagement with the rack 27 or the gear 60 in engagement with the rack 28. The free way 29 is provided to accommodate the gear 59 when the gear 60 is in meshing engagement with the rack 28.

30 The shift rod 22 is provided near its lower end with a shift lever 65 which is fixed thereto and which projects outwardly through a slot 66 in the housing 13 and adjacent the lower end thereof and by means of which the shift rod 22 may be 35 turned on its longitudinal axis for positioning either the gear 59 or the gear 60 in a meshed position, as previously described.

36 In the embodiment as illustrated in Figures 1 to 9, a flanged collar 67 is loosely disposed on the tool bit 35 and seats against the inner end of the bearing 15. The bit shank 36 is provided with a relatively long spline or groove 68 for receiving a key 69 which projects into the bore of a locking disk 70 which is disposed on the shank 36 and rests against the upper end of the flanged collar 67 for slidably keying said disk 70 to the shank 36. A locking lever 71 is swingably mounted at one end thereof on the shift rod 22 above the 40 shift lever 65 and extends substantially diametrically across the housing 13 and outwardly thereof through a slot 72, as seen in Figure 1. The locking lever 71 has an outwardly bowed intermediate portion 73 which extends around the locking disk 70 and which is provided with an inwardly projecting stud or pin 74 for engagement with any one of the notches 75 which open outwardly of the periphery of the disk 70, in one 45 position of the lever 71. A plate 76 is provided with openings for loosely receiving the rods 21 and 22 and the tool bit 36 and rests upon the pivoted end of the lever 71, as seen in Figure 2 and holds said lever 71 against upward displacement on the shift rod 22, on which it is turnably 50 disposed. The plate 76 is in turn held against upward displacement by a collar 77 which is secured to the shift rod 22 and which bears on the plate 76. A collar 78 is fixed to the shift rod 22 adjacent its upper end and has a coil spring 79 bearing thereon and which likewise bears against the cap 14 for urging the collar 77 against the plate 76.

75 Assuming the parts of the tool 12 to be in the positions as illustrated in Figure 2 and assuming that the bit 35 is engaging a screw kerf, by exert-

ing a force against the cap 14 toward the bit 35, the housing 13 together with the core 23, cap 14 and bearing 15 will move relatively to the carriage 39 and bit shank 36 toward the bit and in so moving, the gear 59 by meshing engagement with the rack 27 will be revolved in the direction as indicated by the arrows thereon in Figure 2 for turning the shaft 52 and beveled gears 63 in the same direction to cause the beveled gear 40 and the shank 36 to be revolved in the direction as indicated by the arrow in Figure 2 applied to the gear 40 for exerting a torsional force on the screw engaged by the bit 35 for embedding it in an element. It will be apparent that the inclined disposition of the teeth of the clutch halves 41 and 42 will retain the clutch halves in locked engagement when the beveled gear 40 is thus revolved so that bit shank 36 will turn therewith. When the longitudinal force is released from the cap 14, the compressed spring 55 will return the parts to their retracted positions of Figure 2 by forcing the carriage toward the bearing 15 and the bit shank 36 will be carried with said carriage and will slide through said bearing 15. During this movement, the gear 59, shaft 52 and gear 63 will be revolved in the opposite direction to turn the gear 40 in the opposite direction but the bit shank 36 will not be revolved with the gear 40 in this reverse direction due to the fact that the teeth of the upper clutch half 41 will ride over the teeth of the lower clutch half which will be cammed downwardly thereby against the action of the spring 45 to allow the hub 39 and its clutch half 41 to turn relatively to the clutch half 42 and bit shank 36. By turning the shift rod 22 clockwise as seen in Figure 3 by manual operation of the lever 65, the web 64 thereof will shift the compound gear 56 to the right of its position of Figure 3 to position the gear 60 to mesh with the rack 23 and the gear 59 out of mesh with the rack 27 thereby placing the tool 12 in a geared position for high speed operation and wherein the shaft 52 will be revolved more rapidly in ratio to the translational motion of the housing 13 for revolving the bit 35 at a greater speed and to cause it to make a greater number of revolutions in the movement of the parts from their positions of Figure 2 to their positions of Figure 1. Accordingly, the tool can be used in this last mentioned high speed position where a screw, not shown, is being driven into soft wood, for example, and in its low speed position as illustrated in Figures 2 and 3 where a screw is to be driven into hardwood or where a greater torsional force is required. When it is desired to utilize the tool 12 for extracting a screw, the locking lever 71 is manually swung counterclockwise as seen in Figure 4 to engage the stud 74 with one of the notches 75 to prevent the disk 70 and bit 35 from turning relatively to the housing 13 and bearing 15 so that the tool may then function as a conventional screw-driver.

Obviously, other types of turning tool bits such as drill bits could be substituted for the screw-driver bit 35.

Figures 10 and 11 illustrate a modified means for mounting the locking disk and locking lever, requiring fewer parts and wherein the flanged collar 67 is omitted and the locking disk 70a rests instead on a washer 67a which bears on the inner end of the bearing 15a. The locking lever 71a, which is of a slightly modified shape is swingably mounted at one end thereof on the rod 21a

rather than on the shift rod 22a and instead of the shift rod 22a being provided with a collar 78 and a spring 79, the collar 78a is adjustably secured to the rod 21a above and adjacent the plate 76a and the spring 79a is disposed on the rod 21a between said collar 78a and the plate 76a so that the levers 65a and 71a are disposed in the same plane and the plate 76a is held down at each of its ends by the spring 79a and the collar 77a. If desired, the shift rod 22a may likewise be provided with a collar and spring, corresponding to the collar 78 and spring 79 so that the plate 76a will be yieldably urged downwardly at each end thereof. As the function of the parts shown in the modification of Figures 10 and 11 are the same as the complementary parts illustrated in Figures 1 to 9, a further description thereof is considered unnecessary.

Various other modifications and changes are contemplated and may obviously be resorted to, without departing from the spirit or scope of the invention as hereinafter defined by the appended claim.

I claim as my invention:

25 A thrust actuated turning tool comprising an elongated housing, an elongated bit shank slidably and rotatably disposed in said housing and projecting axially from one end thereof, a stationary rack in the housing, a carriage reciprocally mounted for longitudinal movement in the housing in which one end of the bit shank is non-slidably journaled, a shaft journaled in said carriage, a gear forming a ratchet wheel keyed to the shaft and meshing with said rack, beveled gear 35 means connecting said shaft and bit shank, and spring means yieldably urging the carriage toward one end of the housing for normally holding the housing in a retracted position with respect to the bit shank, said housing being movable against the action of said spring relatively to the bit shank and carriage by a thrust exerted axially thereon for displacing the carriage and bit shank longitudinally toward the end of the housing, opposite to the end in which the bit shank is journaled, for causing the ratchet wheel to be revolved by engagement with said rack for revolving the bit shank, a second, smaller ratchet wheel mounted on said shaft, said ratchet wheels being slidably keyed to the shaft for movement as a unit relatively thereto, a second rack for engaging the second ratchet wheel when the first ratchet wheel is displaced out of engagement with the first rack, and manually actuated shift means including a rod journaled in the housing for rotating about its longitudinal axis and relative to which the carriage is slidably movable for displacing the ratchet wheels as a unit relatively to the shaft for positioning one or the other of the ratchet wheels in engagement with its respective rack to vary the speed of rotation of the bit shank relatively to the speed of sliding movement of the bit shank with respect to said housing.
